United States Patent Office

Des. 190,708
Patented June 20, 1961

190,708

PLASTIC SHEET MATERIAL

Ray Charles Diver, Jr., Cornwall on the Hudson, N.Y., assignor to E. I. du Pont de Nemours and Company,
Wilmington, Del., a corporation of Delaware

Filed Feb. 13, 1959, Ser. No. 54,603

Term of patent 14 years

(Cl. D87—3)

FIG. 1

I claim:

The ornamental design for a plastic sheet material, substantially as shown.
